UNITED STATES PATENT OFFICE.

WILLIAM D. DE LAMARTER, OF ELIZABETH, AND FREDERICK W. WALLACE,
OF PLAINFIELD, NEW JERSEY, ASSIGNORS TO WACLARK WIRE COMPANY,
A CORPORATION OF NEW JERSEY.

ROD-COILING APPARATUS.

SPECIFICATION forming part of Letters Patent No. 694,003, dated February 25, 1902.

Application filed October 11, 1901. Serial No. 78,295. (No model.)

To all whom it may concern:

Be it known that we, WILLIAM D. DE LAMARTER, of Elizabeth, and FREDERICK W. WALLACE, of Plainfield, county of Union, 5 and State of New Jersey, citizens of the United States, have invented certain new and useful Improvements in Rod-Coiling Apparatus, of which the following is a specification, taken in connection with the accompanying drawings, 10 annexed to and forming part of the same.

This invention relates to rod-coiling apparatus such as is used to form wire rod into coils as the rod is delivered from the rolls.

In the accompanying drawings, in which the 15 same reference characters refer to similar parts of the various figures, Figure 1 is an elevation of this apparatus, parts being shown in section. Fig. 2 is a detail sectional view on the line 2 2 of Fig. 1. Fig. 3 is a detail 20 sectional view on a radial plane.

The drum A, which is provided with suitable ribs A' about its periphery, is stationary during the winding of the rod in this apparatus, and it is supported on the arm B' of the 25 hydraulic cylinder B, through which it may be readily raised into position to coil the rod around it or lowered below the level of the operating-floor C to allow the coil of wire rod to be readily removed.

30 The coiler-cone D is formed of a heavy casting and is rigidly fastened to the journal D', supported in a heavy bearing E' at the upper end of the standard or support E. Upon the upper end of the journal is formed the bevel-gear D². This gear is engaged by the bevel-pinion F', splined to the shaft F and driven as desired by suitable fast and loose pulleys F². The shaft F is mounted in the bearings E², which are bolted to the standard E. In 35 this way the coiler-cone is rotated while the drum remains stationary, although the apparatus is effective if the relative movement between these two parts is secured by having the drum rotate and the cone stationary.

40 Upon the coiler-cone are mounted the three guide-rolls H', H², and H³, which project from it in substantially radial planes, the outer end of the rolls in each case being supported by a suitable bracket, the bracket H⁴ (indicated in Fig. 3) serving to support the outer

end of the bearing-bolt H⁶, which passes through the roll H³. Upon the lower end of the roll is formed a suitable flange H⁵, the flange being formed with a curve or fillet joining it to the body of the roll. The lower end 55 of the roll fits within the cavity formed in the coiler-cone D to give a more rigid bearing at the inner end of the guide-roll and to bring the curved flange substantially flush with the surface of the coiler-cone, as shown. This 60 curved flange H⁵ engages the rod and holds it away from the surface of the cone. At the lower edge of the coiler-cone the clearer-roll H is mounted, the bearing-bolt H⁸ of this roll being screwed into a flange formed on the 65 cone. This bearing-bolt is inclined away from the axis of the coiler-cone, as indicated in Figs. 1 and 2. The flange H⁷ of the clearer-roll has a curved formation where it joins the body of the roll, so that it will guide the rod 70 in contact with this flange under normal conditions of operation without abrading the rod. This flange, as indicated in Fig. 2, projects somewhat from the outer surface of the coiler-cone, and the end of the clearer-roll projects 75 considerably below the cone.

The rod-guide G is formed of heavy tubular construction, the antifriction-roll G' being mounted at its upper side near the curve in the guide, and the series of antifriction-rolls G² are mounted on the inside of the curve. As is seen in Fig. 1, the rod-channel D⁸, formed in the journal of the coiler-cone, communicates at its upper end with the rod-guide and at its lower end is substantially tangent to 85 the other surface of the cone.

In operation the wire rod as it is discharged from the rolls is fed through the guide-tube G and down the channel D⁸ of the coiler-cone. The cone being rotated through the means 90 already described, the end of the rod as it lags behind the rotating coiler-cone engages the guide-rolls H', H², and H³, and finally passing over the clearer-roll is coiled about the drum resting on the floor C. The guide-rolls and the clearer-roll serve to prevent the contact of the rod with the sharp lower edge of the coiler-cone, and especially after the rod has passed entirely through the rolls, so 95 that it is no longer fed positively to the coiler, 100

the clearer-roll keeps even the last end of the rod, which must be fed forward by the rotation of the coiler alone, free from the edge of the coiler-cone, which otherwise would abrade and seriously injure it. It will be seen that the guide-rolls and the clearer-rolls are so situated on the cone that the rod as it is fed around the coiler automatically comes into proper relation with them, the rod engaging all of these rolls and coacting properly with the clearer-roll H. The antifriction-rolls in the rod-guide, as is the case with the guide-rolls and the clearer-roll, are especially useful when soft-wire rods, such as copper, are being coiled, since the serious abrasion of the soft rod against the guiding-channels and other parts of the coiler is thereby prevented. These improvements are equally valuable when the drum of the coiler rotates and the cone is stationary.

Numerous modifications in this device may be made without departing from the spirit of this invention. The exact construction of the guide-rolls and the clearer-roll which has been set forth and their exact position in the apparatus may be modified by those skilled in the art. We do not therefore wish to be limited to the disclosure which we have made in this case; but what we do wish to secure by Letters Patent is set forth in the appended claims.

We claim—

1. In rod-coiling apparatus, a slatted drum mounted on hydraulic elevator mechanism, a support, a coiler-cone revolvably mounted in said support to coöperate with said drum, the lower edge of said cone embracing said drum, a guiding-channel through the journal of said cone and communicating with the exterior of said cone, a series of guide-rolls mounted on said cone to guide a rod issuing from said channel in a rearward direction, said guide-rolls being provided with enlarged bearing-flanges at their inner ends and their outer ends being supported by bearing-brackets, a flanged clearer-roll mounted at an inclination in a recess near the edge of said cone to guide the rod away from said edge and a curved rod-guide communicating with said channel, there being an upper antifriction-roll near said curve and a series of antifriction-rolls on the inside of said curve.

2. In rod-coiling apparatus, a curved rod-guide having an antifriction-roll at the upper part of the guide adjacent the curve in the same and also having a series of antifriction-rolls on the inside of the curve, a drum and a relatively rotating coiler-cone coöperating with said drum, the lower edge of said cone embracing said drum, there being a guiding-channel in said cone communicating with said rod-guide, guide-rolls mounted on said drum and a clearer-roll provided with a guiding-flange mounted at the edge of said coiler-cone to guide the rod out of contact with the edge of said cone.

3. In rod-coiling apparatus, a drum and a relatively rotating coiler-cone, a guiding-channel formed in said cone, a series of guide-rolls mounted on said cone to guide the rod issuing from said channel and a flanged clearer-roll mounted at an inclination adjacent the edge of said cone to be engaged by a rod wound by said cone and to guide the end of said rod over the edge of said cone.

4. In rod-coiling apparatus, a drum and a relatively rotating coiler-cone, the base of said cone embracing said drum, a guiding-channel formed in said cone, guides on the surface of said cone to guide a rod issuing from said channel and a flanged clearer-roll mounted at an inclination in a recess near the base of said cone to guide the free end of rod away from the edge of said cone.

5. In rod-coiling apparatus, a drum and a relatively rotating coiler-cone, the base of said cone embracing said drum, means to guide a rod over the surface of said cone and a flanged clearer-roll mounted in the edge of said cone to guide the rod away from said edge.

6. In rod-coiling apparatus, a drum and a relatively rotating coiler-cone the base of said cone embracing said drum, guides formed on said cone and a flanged clearer-roll mounted at an inclination in a recess in the lower edge of said cone to be engaged by a rod passing out of contact with said guides and to guide said rod away from the edge of said cone.
